ABSTRACT: A lamp receptacle for use in a lamp socket assembly adapted to receive at least two elongated lamps each of which has two end pins at each end, one side of the receptacle having first and second slots therein, each of the slots being adapted to receive the two end pins at one end of one of the lamps, each of the slots having at least one slot extension connected to the slot and extending to a point spaced from the slot, each of the slot extensions being adapted to receive and hold one of the end pins received in each of the slots when, after the end pins have been inserted into the first and second slots respectively, each lamp is moved in a different direction to place the end pins into the respective slot extensions, and the slot extension of the first slot extends in one direction and the slot extension of the second slot extends in a generally opposite direction. Preferably, the slot extensions are arcuate so that the lamps are rotated in opposite directions to rotate the end pins into the arcuate slot extensions. Also, preferably, end pin retaining means are provided adjacent each slot extension to retain the respective end pins in the slot extension and, if desired, to electrically connect the end pins to a source of electric energy when the end pins of each lamp are inserted in the receptacle. The invention also includes a resilient clip comprising a base portion, a spring arm connected at one end to the base portion, and a detent connected to the other end of the spring arm.

LAMP RECEPTACLE

BACKGROUND OF THE INVENTION

1. Field of the Invention

The field of this invention is that of a lamp receptacle for use in a lamp socket assembly. The field of this invention is also that of a resilient clip for use in a lamp receptacle. More specifically, the field of this invention is also that of a lamp receptacle for use in a lamp socket assembly wherein an identical lamp receptacle is used at each end of the lamp socket assembly, obviating the need for a left-hand receptacle and a right-hand receptacle and thereby reducing the cost of the lamp socket assembly.

2. Description of the Prior Art

The prior art is replete with lamp receptacles for use in lamp socket assemblies and in particular for use in fluorescent lamp socket assemblies. However, the prior art lamp socket assemblies for mounting elongated or tubular lamps, such as fluorescent lamps, have not always provided a lamp receptacle which could be used interchangeably at either end of the assembly. In other words, in many prior art lamp socket assemblies a right-hand receptacle and a left-hand receptacle were provided which were similar but not identical to each other. These right- and left-hand receptacles were designed so that an elongated lamp such as a fluorescent lamp can be inserted into the right-hand receptacle and the left-hand receptacle and then rotated into a fastened position within the lamp socket assembly.

Also, prior art lamp receptacles for use in lamp socket assemblies have not always been of a simple compact construction whereby the receptacle takes up a minimum of space within the lamp socket assembly. Furthermore, prior art lamp socket assemblies have not always provided a lamp receptacle for mounting a fluorescent lamp of the type having two end pins at each end, at a specific angle, i.e. with at least one end pin of each lamp rotated a specific angular distance when the lamp is inserted in the lamp socket assembly.

SUMMARY OF THE INVENTION

One object of this invention is to provide a lamp receptacle which is so constructed that two of the lamp receptacles can be situated at each end, respectively, of a lamp socket assembly for mounting both ends, respectively, of two lamps.

Another object of this invention is to provide a lamp socket assembly having two identical lamp receptacles, one at each end of the assembly, for mounting two lamps of the type having two end pins at each end wherein the end pins are received in the receptacles and one lamp is rotated in one direction until the end pins of the lamp are fastened within the lamp receptacles and the other lamp is rotated in the opposite direction until the end pins of the other lamp are fastened within the lamp receptacles.

A further object of this invention is to provide a lamp receptacle having end pin retaining means for retaining at least one end pin of an elongated lamp within the lamp receptacle.

A still further object of this invention is to provide resilient clips for use in a lamp receptacle all of which clips are formed from an L-shaped strip of metal but with half of the clips formed as mirror images of the other half of the clips.

The invention achieves these and other objects, including those inherent therein, by providing a lamp receptacle for use in a lamp socket assembly adapted to receive at least two elongated lamps each of which has two end pins at each end, one side of the receptacle having first and second slots therein, each of the slots being adapted to receive the two end pins at one end of one of the lamps, each of the slots having at least one slot extension connected to the slot and extending to a point spaced from the slot, each of the slot extensions being adapted to receive and hold one of the two end pins received in each of the slots when, after the lamps have been inserted in the first and second slots, respectively, each lamp is moved in a different direction to place the end pins into the respective

slot extensions, the slot extension of the first slot extending in one direction and the slot extension of the second slot extending in a generally opposite direction.

The invention achieves other of its objects by providing a resilient clip for retaining an end pin of a lamp in a lamp receptacle, the clip comprising a base portion, a spring arm connected at one end to the base portion, and a detent connected to the other end of the spring arm.

BRIEF DESCRIPTION OF THE DRAWINGS

FIG. 1 is an exploded perspective view of a preferred embodiment of the lamp receptacle of this invention;

FIG. 2 is a front elevational view of the lamp receptacle shown in FIG. 1;

FIG. 3 is a back elevational view of the housing of the lamp receptacle shown in FIG. 1;

FIG. 4 is a front elevational view of the terminal block of the lamp receptacle shown in FIG. 1;

FIG. 5 is a sectional view taken along lines 5-5 of FIG. 2;

FIG. 6 is a sectional view taken along lines 6-6 of FIG. 4;

FIG. 7 is an enlarged perspective view of one of the resilient clips shown in FIG. 1;

FIG. 8 is an enlarged plan view of an L-shaped strip of metal which is formed into the resilient clip shown in FIG. 7;

FIG. 9 is a perspective view of the lamp receptacle shown in FIG. 1 showing portions of two elongated lamps in phantom lines;

FIG. 10 is a front elevational view of the lamp receptacle shown in FIG. 1 showing portions of the end pins of two lamps received in the arcuate slot extensions.

DESCRIPTION OF THE PREFERRED EMBODIMENTS OF THE INVENTION

A fluorescent lamp receptacle is generally indicated at 10 in FIG. 1. The receptacle 10 comprises a housing 12 and a terminal block 14, which are preferably made from an insulating material such as a moldable plastic material. Four resilient spring clips 16, 17, 18 and 19 are secured to the front face 20 of the terminal block 14. In the illustrated embodiment, the terminal block 14 has four notches 22, 23, 24 and 25 which receive respectively an attaching flange of each of the clips 16, 17, 18 and 19. These notches 22-25 are formed in and transversely of the front face 20 parallel to each other. One pair 22, 23 of the notches 22-25 are disposed on one side of the front face 20 and the other pair 23, 24 of the notches 22-25 are disposed on the other side of the front face 20, as shown in FIGS. 1 and 4, with a centrally disposed locating surface 28 separating the two pairs of notches. If desired, the locating surface 28 can be spaced from the front face 20.

The housing 12 comprises two end walls 30 and 32 and three sidewalls 34, 35 and 36, as shown in FIGS. 1 and 3. In the embodiment illustrated, the sidewall or side 35 can be considered the front sidewall while the sidewalls 34 and 36 can be considered as the top and bottom walls respectively. The side opposite the sidewall 35 is open to receive the terminal block 14. Inside of the housing 12 is a raised portion 38, which is disposed substantially midway between the end walls 30 and 32 and which extends from the front sidewall 35 toward the open side of the housing 12, as shown in FIGS. 3 and 5. When the housing 12 and the terminal block 14 are assembled, the locating surface 28 engage the inner surface 39 on the raised portion 38. If desired, an adhesive can be disposed between the surfaces 28 and 39 for securing the housing 12 to the terminal block 14. In some situations, use of an adhesive to secure the housing 12 to the terminal block 14 will simplify assembly of the lamp receptacle 10 and also reduce the cost of manufacturing the lamp receptacle 10.

In the embodiment illustrated in FIG. 5, a rivet 40 is used to fasten the housing 12 to the terminal block 14. For this purpose, a first bore 41, counterbored at 42, is formed in the terminal block 14 and a second bore 43, counterbored at 44, is formed in the front sidewall 35. Typically, the rivet is staked

over, as indicated at 47 in FIG. 5, to secure the terminal block 14 and the housing 12 together. Of course, other fastening means such as a drive pin or screw (and nut) can be used.

In some lamp socket assemblies, when a rivet, screw (and nut) or drive pin is used (particularly a screw) to fasten the housing 12 to the terminal block 14, the housing 12 can be removed from the terminal block 14 by removing the rivet, screw or drive pin, to allow for repair or replacement of parts, (e.g. the clips 16-19) in the lamp receptacle 10. In these lamp socket assemblies the receptacle 10 is mounted in the assembly by securing the back side or surface 48 (FIGS. 5 and 6) of the terminal block 14 to the frame of the lamp socket assembly (not shown) by an adhesive or other suitable fastening means. To facilitate use of an adhesive back surface 48 is preferably a planar surface.

In one embodiment of the invention, the lamp receptacle 10 is secured to an L-shaped mounting bracket 49, shown in phantom lines in FIG. 5. The bracket 49 includes two frame sections 50 and 51. In FIG. 5, the frame section 50 is disposed generally horizontally and the frame section 51 is disposed generally vertically. The lamp receptacle 10 is positioned on the bracket 49 with the bottom wall 36 resting on the frame section 50 and the back surface 48 flush against the frame section 51. In this embodiment, a longer rivet 40a, shown in phantom lines, is inserted through the bores 41 and 42 and through a hole in the frame section 51, and then staked over at 47a to secure both the housing 12 and the terminal block 14 to the bracket 49.

Each one of the clips 16, 17, 18 and 19 is secured in a respective notch 22, 23, 24, or 25 by a drive pin 52, 53, 54 and 55, as shown in FIGS. 1, 4 and 6. Each one of the clips 16, 17, 18 and 19 is generally S-shaped. All of the clips are formed from an L-shaped piece of metal 56 (FIG. 8). However, some of the clips are formed with the attaching flange, such as flange 57 of clip 18, extending on one side of the clip 18, while other of the clips have the attaching flange, such as flange 58 of clip 17 extending on the other side of the clip 17. In other words, some of the clips are mirror images of the other clips, i.e. the clips 16 and 17 are mirror images of the clips 18 and 19. Since each of the clips are essentially the same, only one clip, clip 17, will be described in detail.

As shown in FIG. 7, the clip 17 comprises an attaching flange 58 having an opening 59 therein for receiving drive pin 53 when the clip 17 is mounted in the notch 23 in the terminal block 14. The basic components of the clip 17 are the attaching flange 58, an L-shaped base or support portion 60 including two leg sections 61 and 62, a spring arm 63 and a detent or detent portion 64. The attaching flange 58 is connected to (i.e. integral with) the leg section 61 while one end of the spring arm 63 is connected to (i.e. integral with) the leg section 62. The detent 64 is connected to the other end of the spring arm 63. Preferably, the detent 64 is a rounded extension of the arm 63 formed by bending over the other end of the arm 63.

It will be readily understood that the forming of the clips 16, 17, 18 and 19 from identical L-shaped strips of metal will facilitate the manufacture of the lamp receptacle 10 as well as minimize the cost for constructing the clips 16, 17, 18 and 19. Also, as will be more fully explained below, each of the clips can serve the dual function of (a) holding an end pin of an elongated tubular lamp within the lamp receptacle 10 and, (b) providing an electrical connection to the end pin, while allowing the pins to be inserted through the top wall 34, i.e. the clips 16, 17, 18 and 19 do not interfere with the introduction or insertion of the end pins of the elongated or tubular lamps through the top wall 34 into the lamp receptacle 10.

In the embodiment of the invention illustrated in FIGS. 1, 4 and 5, wire conductors 72, 73, 74 and 75 are connected by means of lugs 76, 77, 78 and 79 to each one of the clips 16, 17, 18 and 19. The lugs 76, 77, 78 and 79 can be of any known type such as a bifurcated lug or an eyelet-type lug. Each of the lugs 76-79 is disposed beneath the respective attaching flange 57 or 58 of each of the clips 16-19 and then secured

between the attaching flanges 57 or 58 and the respective notches 22, 23, 24 or 25 in the terminal block 14 by the respective drive pins 52, 53, 54 and 55.

Passage means for the entry or insertion of the wire conductors 72, 73, 74 and 75 into the lamp receptacle 10 is provided in the form of openings 81, 82, 83 and 84 (FIGS. 2 and 3) in the front sidewall 35 of the housing 12. It is to be appreciated that these openings can be formed in the end walls 30 or 31 or in the other sidewalls 34 and 36 of the housing 12. On the other hand, a different type of passage means in the form of one or two larger openings can be provided in either the housing 12 or the terminal block 14 for entry of the wire conductors 72, 73, 74 and 75 into the lamp receptacle 10.

In some applications, such as, for example, where only two of the clips 16-19 serve as electric contacts, less than four conductors will be needed for the two lamps inserted in the lamp receptacle 10, and less than four openings will be needed. In these applications another form of passage means may be provided.

Returning now to the construction of the housing 12, the first and second slots 91 and 92 are provided in the sidewall 35 of the housing 12 as shown in FIGS. 1, 2 and 3. Preferably, the slots 91 and 92 are parallel to each other. However, the slots 91 and 92 need not be parallel. It is essential though, that they be mirror images of each other so that two identical receptacles 10 can be used at each end of a double lamp socket assembly. Third and fourth parallel slots 93 and 94 (FIG. 1) are formed in the top sidewall 34 of the housing 12. The sidewalls 34 and 35 are adjacent one another and form an edge 96 therebetween. The first and second slots 91 and 92 extend to the edge 96. The third and fourth parallel slots 93 and 94 also extend to the edge 96 to mate or connect with the first and second slots 91 and 92.

In the embodiment illustrated, the first slot 91 is provided with a pair of arcuate slot extensions 97 and 98. Likewise, the second slot 92 is provided with a pair of arcuate slot extensions 99 and 100.

The slots 91 and 92 are each designed to receive the two end pins 101a and 101b or 101c and 101d of a conventional fluorescent lamp 102a or 102b shown in phantom lines in FIGS. 9 and 10. The slots are also designed so that electrical contact means (e.g. clips 16-19) can contact the end pins for connecting a heating element or a filament at each end of each fluorescent lamp 102a and 102b to a source of electric energy and also for connecting an electric potential across each lamp 102a and 102b.

An important aspect of the invention is that one pair of the arcuate slot extensions 97, 98 extend in one rotational direction and the other pair of arcuate slot extensions extend in the opposite rotational direction, with each of the arcuate slot extensions being connected to a respective slot 91 or 92 and extending to a point spaced from the respective slot 91 or 92, whereby the end pins 101a, 101b of one lamp received in the first slot 91 are rotated in one direction to a fastened position and the end pins 101c, 101d of the other lamp 102b received in the second slot 92 are rotated in the opposite direction to a fastened position.

In some applications one arcuate slot extension of each pair of arcuate slot extensions can be omitted, e.g. arcuate slot extensions 98, 100 or 97, 99 can be omitted. Such a construction might be preferred where heating elements are not utilized in the fluorescent lamp and only one end pin at each end of the fluorescent lamp is needed for placing an electric potential across the lamp.

With the arcuate slot extensions formed in the manner stated, each lamp receptacle 10, when facing another receptacle 10, will be a mirror image of the other receptacle 10. Thus, in a lamp socket assembly two lamp receptacles 10 are mounted in spaced apart relationship with sidewall 35 on one lamp receptacle 10 facing sidewall 35 on the other lamp receptacle 10. Two lamps then can be mounted between the two receptacles with the end pins 101a, 101b on one end of the one lamp 102a being received in the first slot 91 in one

lamp receptacle and the end pins (not shown) at the other end of that lamp 102a being received in the second slot 92 in the other lamp receptacle (not shown). The end pins 101c, 101d at one end of the other lamp 102b are received in the second slot 92 in the one receptacle and the end pins (not shown) at the other end of the second lamp are received in the first slot 91 in the other lamp receptacle (not shown). After the first lamp is inserted in the respective first and second slots 91, 92 of the two lamp receptacles 10, it is rotated in one direction to place the end pins at each end of the lamp into the respective arcuate slot extension 97 and 98 in the one lamp receptacle 10 and the respective arcuate slot extensions 99 and 100 in the other lamp receptacle 10. On the other hand, the second lamp is rotated in the other or opposite rotational direction to place the end pins at each end of the second lamp into the respective arcuate slot extensions 99 and 100 in the one lamp receptacle and the respective arcuate slot extensions 97 and 98 in the other lamp receptacle respectively.

The third and fourth slots 93, 94 facilitate the insertion of the two lamps 102a and 102b into the lamp receptacle. When inserting the one lamp 102a into the lamp receptacle, the two end pins 101a, 101b are first inserted into the third slot laterally of, along and parallel to the third slot and then into the first slot, transversely of the first slot until the two end pins 101a, 101b of the one lamp 102a are aligned with the respective arcuate slot extensions 97, 98, whereupon the one lamp 102a is rotated in one rotational direction to place at least one of the two end pins 101a or 101b of the lamp 102a into one of the arcuate slot extensions 97 or 98. In like manner the other lamp 102b is first inserted into the fourth slot 94 and then into the second slot 92. When the end pins 101c and 101d are aligned with the slot extensions 99 and 100, the other lamp 102b is rotated in the other or opposite rotational direction to place at least one of the two end pins 101c and 101d into one of the arcuate slot extensions 99 or 100.

As shown in FIG. 2, each of the clips 16, 17, 18 and 19 is situated adjacent one of the arcuate slot extensions 97-100 so that the detent portion 64 of each of the clips extends into the path of one of the end pins 101a, 101b, 101c and 101d of the lamps 102a and 102b when they are rotated into the arcuate slot extensions 97, 98, 99 and 100. In this way, the resilient spring clips 16-19 provide resilient holding or retaining means for engaging and retaining the respective end pins of the respective lamps in the arcuate slot extensions 97-100 when the pins are inserted or placed into the arcuate slot extensions 97-100. As an end pin engages the detent portion 64, the spring arm 63 allows the detent portion 64 to be moved out of the path of the end pin under the pressure of the end pin. After an end pin has been moved past detent portion 64, the detent portion 64 is returned to its previous position by spring arm 63. The spring arms 63 have sufficient stiffness or rigidity to hold or retain the end pins of the lamps in the respective arcuate slot extensions 97-100 and yet have sufficient resiliency to permit the end pins to be easily moved in and out of the respective arcuate slot extensions 97-100 past the detent portions 64.

Each arcuate slot extension 97, 98, 99 and 100 is provided with a rounded end portion 103, 104, 105 and 106 against which the respective end pins of each lamp are seated. The detent portions 64 extend into the path of the end pins received in the arcuate slot extensions 97-100, and are arranged or aligned so as to snugly and resiliently hold the respective end pins of each lamp 102a and 102b against the rounded end portions 103, 104, 105 and 106 of the arcuate slot extensions 97, 98, 99 and 100. The arcuate slot extensions 97-100 and the rounded end portions 103-106 thereof are formed so that the lamps, mounted in the first and second slots 91 and 92 respectively, are rotated in opposite directions the same angular distance before the end pins of each lamp 102a and 102b are seated against the respective rounded end portion 103-106 of the respective arcuate slot extension 97-100.

In the embodiment shown in FIG. 2, the center point of the curve of each rounded extension 103 and 104, or 105 and

106, lies on a line 109, or 110, which intersects the respective centerline 111, or 112, of the first slot 91, or the second slot 92. Preferably, the two arcuate slot extensions 97 and 98 of the first slot 91 extend respectively in one arcuate or circular direction about a center point situated approximately on the centerline 111 of the first slot 91 and the two arcuate slot extensions 99 and 100 of the second slot 92 extend respectively in an opposite arcuate or circular direction about a center point situated approximately on the centerline 112 of the second slot 92. With the arcuate slot extensions 97-100 constructed in this manner the angle A between a horizontal datum line 114 and the line 109 passing through the centers of the curves of the rounded end portions 103, and 104 is equal to the angle B between the horizontal datum line 114 and the line 110 passing through the centers of the curves of the rounded end portions 105 and 106.

From the foregoing specification those skilled in the art will appreciate that this invention, described above and illustrated in the accompanying drawings, provides a simple and compact lamp receptacle and a simple resilient clip which can be easily and inexpensively manufactured. It is also to be appreciated that two of the lamp receptacles described and illustrated, can be easily secured into a double lamp socket assembly by an adhesive, by a rivet, or by a screw and nut. Furthermore, the lamp receptacle can be formed with a plurality of even numbered slots similar to slots 91 and 92, e.g. two, four, six, eight, etc., with the first slot being a mirror image of the second slot, the third slot being a mirror image of the fourth slot, etc. Such modified receptacles then can be used at each end of a multiple (even numbered) lamp socket assembly.

I claim:

1. A lamp socket assembly which is adapted to receive at least two elongated lamps each having two end pins at each end, said assembly including two identical, spaced apart lamp receptacles with each of said lamp receptacles comprising:
  - a generally rectangular box-shaped housing made of an insulating material;
  - a first elongated side of said housing having at least one set of first and second main slots therein which are mirror images of each other;
  - each main slot defining an unobstructed end pin receiving channel for receiving the two end pins at one end of one of said lamps;
  - a second elongated side of said housing adjacent said first elongated side having at least one set of parallel slots therein which individually connect with a respective one of said first or second main slots to permit insertion of said lamp end pins into said receptacle in a direction transverse to the longitudinal axes of said end pins;
  - each main slot having a first arcuate slot extension communicating with the inner end of said main slot and extending laterally of said main slot from said inner end thereof to a point spaced from the centerline of said main slot and a second arcuate slot extension communicating with said main slot at a point spaced from said inner end of said main slot and extending laterally of said main slot to a point spaced from said centerline of said main slot;
  - each one of said arcuate slot extensions having an end portion against which a lamp end pin can be seated;
  - said two arcuate slot extensions which communicate with said first main slot extending from opposite sides of said centerline of said first main slot in one arcuate direction a predetermined angular extent about a center point situated approximately on said centerline of said first main slot and said two arcuate slot extensions which communicate with said second main slot extending from opposite sides of said centerline of said second main slot in an opposite arcuate direction the same predetermined angular extent about a center point situated approximately on said centerline of said second main slot, whereby, after each pair of end pins is received in one of said main slots, said lamps can be rotated the same angular extent but in opposite arcuate directions to place each end pin against

the end portion of one of said slot extensions of said first or second main slot;
 a generally rectangular terminal block made of an insulating material and secured to said housing opposite said first elongated side of said housing;
 at least four, electrically conductive, resilient contacts fixed to said terminal block at spaced apart locations thereon and extending from said terminal block into said housing;
 means for connecting each of said contacts to a source of electric potential;
 each of said contacts including a base portion fixed to said terminal block, a spring arm connected at one end to said base portion, and a detent portion connected to the other end of said spring arm;
 said terminal block having means for engaging said base portion of each of said contacts to prevent turning of each contact in a direction generally parallel to said terminal block while permitting flexing of said spring arm of each

of said contacts in said direction generally parallel to said terminal block;
 each one of said detent portions extending outwardly from said terminal block and laterally toward, but not into, a plane containing the centerline of one of said parallel slots and the centerline of one of said main slots, and being normally positioned behind one of said arcuate slot extensions and in the path of an end pin received in said one of said arcuate slot extensions; and,
 each of said detent portions serving as a retaining clip which is deflected in said direction generally parallel to said terminal block by an end pin moving into said one of said arcuate slot extensions and which returns to its normal position, after said pin is moved past said detent portion, for holding said end pin against the end portion of said one of said arcuate slot extensions.
